(57) **CLAIM**

The ornamental design for a rotational nozzle, as shown and
described.

DESCRIPTION

FIG. 1 is a perspective view of the rotational nozzle of the
present design.

FIG. 2 is a left side elevation view of the design of FIG. 1.

FIG. 3 is a bottom plan view of the design of FIG. 1.

FIG. 4 is a top plan view of the design of FIG. 1.

FIG. 5 is a right side elevation view of the design of FIG. 1.

FIG. 6 is a front elevation view of the design of FIG. 1; and,
FIG. 7 is a rear elevation view of the design of FIG. 1.

1 Claim, 4 Drawing Sheets
